Primary Examiner—Ruth McInroy*Attorney, Agent, or Firm*—Nixon & Vanderhye**[57]****CLAIM**

The ornamental design for a microwave oven, as shown and described.

DESCRIPTION

FIG. 1 is a top, front and right side perspective view of a microwave oven according to my design;
 FIG. 2 is a top plan view thereof;
 FIG. 3 is a front elevational view thereof;
 FIG. 4 is a right side elevational view thereof;
 FIG. 5 is a left side elevational view thereof;
 FIG. 6 is a rear elevational view thereof;
 FIG. 7 is a bottom plan view thereof;
 FIG. 8 is a front elevational view thereof with the microwave door in an open position;
 FIG. 9 is a front elevational view of a second embodiment of microwave oven according to my design;
 FIG. 10 is a top plan view thereof;
 FIG. 11 is a right side elevational view thereof, the left side elevational view being the mirror-image thereof;
 FIG. 12 is a rear elevational view thereof; and,
 FIG. 13 is a bottom plan view thereof.
